UNITED STATES PATENT OFFICE

JOHN W. SHAW, OF NORWOOD, NEW JERSEY, ASSIGNOR TO BING & BING, INC., A CORPORATION OF NEW YORK

AWNING FIXTURE

Application filed May 24, 1928. Serial No. 280,150.

My present invention is concerned primarily with awnings, more especially with those of the spring roller type, and relates particularly to operating means therefor by which the awning may be adjusted from the inside of a room without opening the window.

An object of the invention is to provide a device of the character noted above, which may be interchangeably used with various types of spring roller awnings and which is universally applicable to a wide range of window sizes and window styles, both of the drop sash and of the fixed sash types of window.

The usual spring roller awnings embody in the rollers a ratchet mechanism which is more or less flimsy, and which is so exposed to the weather that it may quickly become rusty and ineffective. In consequence when the awning, in partially or fully lowered position is blown about by the wind, this ratchet mechanism is sometimes released or broken, and the awning rolls up with a snap and a bang, frequently damaging both the awning and its supporting fixtures and making a most disconcerting noise.

It is accordingly an object of the invention to provide an awning operating means of the above type, in which the flapping or undesired release of the holding mechanism is precluded and which mechanism yet readily responds to the usual manual operation to raise or lower the awning.

Another object is to provide a substantially fool proof operating mechanism adapted to withstand hard usage and so designed that its careless manipulation cannot result in damage to either the awning or the operating gear.

According to my invention the operating tape is provided with an automatic check arranged in protected position out of the weather, preferably within the room, and which may serve either to supplement the roller ratchet mechanism or as a substitute therefor.

The check normally prevents spring-roller urged movement of the tape. A slight man-

ual pull on the pendent end of the tape, however, suffices to disengage it from the check so that it may run freely outward as the spring roller winds up the awning.

The tape passes over guides on bracket fixtures arranged adjacent the top of the sash and on opposite sides thereof, one of these fixtures also carrying the tape check. These brackets are preferably each made of a pair of relatively slidable parts so that they may be arranged to fit any standard type of sash through which the tape is to be guided.

Another object is to provide a mechanism with which the above noted advantages are had without sacrificing any of the meritorious features and noteworthy advantages of the awning operating means disclosed in my prior application Serial No. 171088 filed Feb. 26, 1927, on which the present invention is an improvement.

Other objects of the invention are to provide a mechanism of simple practical construction which may be conveniently attached to a window, which will be rugged, durable and efficient in use and which is well suited to the requirements of economical manufacture.

With the above noted and other objects in view, the invention consists in certain novel features of construction and combinations and arrangements of parts which will be more fully hereinafter described and pointed out in the claims.

The invention may be more fully understood from the following description in connection with the accompanying drawings wherein:

Fig. 1 is a perspective view showing the outside of a window equipped with an awning (shown partly lowered) and adapted to be operated by the mechanism of the present invention.

Fig. 2 is a view on a larger scale in vertical section taken approximately on the line 2-2 of Fig. 1.

Fig. 3 is a sectional plan view taken approximately on the staggered line 3-3 of Fig. 2.

Fig. 4 is a vertical sectional detail taken approximately on the line 4—4 of Fig. 2.

Fig. 5 is a vertical sectional view on the line 5—5 of Fig. 3.

Fig. 6 is a view similar to Fig. 2 but showing the operating mechanism applied to another type of sash and showing the operating flexible device drawn to a position in which the spring roller is free to wind up the awning, and

Fig. 7 is a view in section through an awning wound about a spring roller in which no ratchet mechanism is used.

In the drawings an awning 17 is shown wound on a spring roller 12, the usual round gudgeon 13, and flat gudgeon 14 at opposite ends of the roller being mounted in conventional hangar brackets 15, 16 secured to the top of the window frame 10 exteriorly of the sash 11, the latter bracket having the usual slot for the flat gudgeon.

A cross bar passing through a hem 18 near the free end of the awning is formed integral with a pair of arms 19, the ends of which are pivoted to brackets 20 secured to the uprights of the window frame 10. The weight of the arms 19 and their associated cross bar tends to unroll the awning while the coiled torsional spring 21 secured within the roller 12 tends to roll up the awning. This spring is strong enough to normally overcome the weight of the arms and cross bar. In order to lower the awning, a positive unwinding torque must be applied to the roller and suitable ratchet mechanism 48 serves to block the rewinding action of the spring 21. As is the common practice the spring 21 is wound about the usual metal core 46 to the hub 47 of the flat gudgeon 14.

The means for unwinding the awning 17 against the action of the spring 21 includes the usual flexible device 32 preferably in the nature of a tape, one end of which is rolled about the roller 12 between the convolutions of the awning and anchored with the edges of the awning to the roller by the anchoring notch 33.

The mechanism thus far described taken by itself is not my invention, the latter being more particularly concerned with the provision of the tape checking mechanism for positively preventing inadvertent spring winding of the awning and the construction of the brackets 60 and 70 which renders them universally adjustable.

The flexible tape 32 passes through a slot 37 at the upper edge of the window pane shown of the fixed sash type and depends into the room terminating in a handle loop 43.

Arranged at the outside and inside of the sash are tape guiding brackets 60 and 70 the details of which will be later described. These brackets mount rollers such as the

rollers 35, 36 of the outer bracket and the roller 38 of the inner bracket for guiding the tape. The inner bracket also carries my improved checking means which will be more fully described.

The brackets 60 and 70 may be generally similar to those disclosed in my copending application above identified in that they include attaching portions 22 and 27 respectively and flanged channel forming portions 24 and 30 respectively within which the guide rollers are mounted. These channel portions are disposed closely adjacent the window pane and facing each other at opposite sides of the sash.

An improvement over my prior disclosure however is the manner in which the brackets 60 and 70 are rendered universally adjustable to fit various sizes and styles of windows. The channel portion 24 of the bracket 60 is adjustable along vertical slot 26 in the depending plate portion 23, this adjustment being effected by headed screws 25 working through the slot and engaging the channel piece. A similar adjustment of the channel piece 31 may be effected by adjusting screws provided in channel piece 30 to work through slot 29 in the coacting portion 28.

The present brackets are also similar to those disclosed in my copending application in that both brackets are provided with tape guide rollers 36 and 38 near their tops which guide the travel of the tape through the slot 37 in the window pane. Also the channel piece 24 is preferably of greater length than the channel piece 30 and mounts a guide roller 35 well below the plane of the upper rollers 36, 38. Thus as the tape 32 from the roller 12 is led through the opening 34 in the back of the channel 24 and passed around under the roller 35 a down pull is exerted on the spring roller 12 which is thus effectively prevented from jumping out of its brackets.

While the adjustable nature of the bracket fixtures herein illustrated is desirable for rendering them universally applicable to several styles of sashes, it is obviously within the scope of the invention to make such brackets as integral one piece stampings or castings when turned out in large quantities for standard size windows.

The tape checking means is arranged within the channel 30 of the bracket 70 below the guide roller 38. This means may include a knurled eccentric 39 hanging freely on a pivot pin 40 connecting the flanges of the channel 30. This eccentric is preferably provided with a spur 49 near its lower end. The bail 41 pendent from the member 30 is preferably provided with a heavy roller 42 on its cross bar. This bail normally tends to move the handle end of the tape 32 to a position closely adjacent the

window pane and to hold the tape in frictional engagement with the eccentric 39. The tape is led around the roller 38 between the eccentric 39 and the back of the channel 30 and thence forwardly through the bail 41.

The action of the mechanism is substantially as follows: With the parts in the position of Figs. 1 and 2, the awning is lowered by grasping the handle 43 and exerting a downward pull thereon. As the tape is drawn off the roller 12 the spring 21 is wound and the weight of arms 19 and their associated cross bar gravitationally extends the awning 17 as it is unwound from its roller. As the tape 32 is released the spring roller will immediately tend to rewind the tape and the awning. As a consequence, the tape 32 will frictionally engage the eccentric 39, swinging this eccentric to the position of Fig. 2 and firmly jamming the tape between the back of the channel 31 and the eccentric. Any further pull on the tape in an outward direction merely serves to tighten this binding action on the tape between the eccentric and the back of the channel piece 30.

The spur 49 ensures the frictional engagement of the outwardly drawn tape with the eccentric since the tape is always moved into engagement with said spur by the action of the roller 42 in its inward swing toward the window pane.

When it is desired to permit the spring roller to wind up the awning, the end of the tape is grasped and drawn rearward or downward, thereby swinging the roller 43 well rearwardly and disengaging the tape from the spur 49 of the eccentric 39. As long as the inner end of the tape is manually held from returning to the position of Fig. 2, the tape may run freely in an outward direction without any interference from the eccentric.

It may be noted that the action of the eccentric and its associated tape engaging mechanism is entirely independent of the usual pawl and ratchet mechanism of the roller and is much more positive in operation than such mechanism. The tape engaging means dispenses with the need for conventional ratchet and pawl mechanism and the simplified spring roller of Fig. 7 devoid of ratchet mechanism may be conveniently used. The parts of Fig. 7 bear the same reference numerals as the corresponding parts of Fig. 3.

Even though the awning is in fully or partially lowered position and is being blown about by the wind in a manner in which would render the ordinary ratchet and pawl mechanism of the roller ineffective, there is no danger of the eccentric tape retarding means failing to function, and there is no danger of the spring roller being

released to wind up the awning with an undue rapidity which might injure the mechanism.

In Fig. 2 it will be noted that the channel members 24, 30 are disposed as closely as possible to the window pane and that their upper edges abut the lower face of the upper cross bar 50 of the fixed sash 11. In Fig. 6, however, the channel pieces 24 and 30 are so adjusted that they abut the window frame 10 immediately adjacent the inner and outer faces of the upper cross bar 51 of a sliding sash. Here the tape passes through a notch 52 in the top of the cross bar 51 so that it will not interfere with the usual raising and lowering of the sliding sash.

In Fig. 6 I have also shown a slight modification in that the bracket plate 28 is shortened by cutting away its lower end so that the bail 41 and associated roller 42 may swing rearwardly without interference from the plate 28.

The specific bracket construction herein illustrated is especially designed to render the mechanism entirely fool-proof and to prevent faulty winding of the awning on its roller even if the tape is carelessly handled or jerked. The flanges of the channel pieces 24 and 30 retain the tape 32 against lateral movement in such a manner that only a true torque may be applied tangentially to the roller. The tape cannot slip sideways with a resultant drawing off action or partial longitudinal strain being imposed on the roller which might crease or jam the awning.

The bracket fixtures of the present invention are devoid of springs, gears and delicate mechanism which might be injured by careless or strenuous handling of the manipulating tape, the tape retarding mechanism which is carried by the inner bracket being both simple and rugged in construction and positive and efficient in its action. All of the guide rollers are preferably supported on roller bearings so that their action will be noiseless and so that they will have no appreciable frictional retarding action on the tape as the tape is drawn over them in either direction.

It will be seen that there is herein described a device in which the several features of this invention are embodied and which device in its action attains the various objects of the invention and is well suited to meet the requirements of practical use.

As many changes could be made in the above construction and many apparently widely different embodiments of the invention could be made without departing from the scope thereof, it is intended that all matter contained in the above description or shown in the accompanying drawings shall

be interpreted as illustrative and not in a limiting sense.

Having thus described my invention, what I claim as new and desire to secure by Letters-Patent is:—

1. Operating mechanism for a spring roller type awning mounted exteriorly of a sash, comprising an operating tape having its handle and disposed at the interior of the sash, and means disposed interiorly of the sash normally automatically preventing the spring roller actuated movement of the operating tape.

2. Operating mechanism for a spring roller type awning mounted exteriorly of a sash comprising an operating tape therefore having its handle end disposed interiorly of the sash, and tape checking means disposed interiorly of the sash and acting automatically to prevent the tape from being drawn outwardly by the roller.

3. Operating mechanism for a spring roller type awning mounted exteriorly of a sash, including an operating tape having its handle end disposed at the interior of the sash, and means disposed interiorly of the sash normally automatically acting to prevent the spring roller actuated movement of the operating tape and means whereby a slight manual pull on the inner end of the tape renders said means inoperative.

4. Operating mechanism for a spring roller type awning mounted exteriorly of a sash, including an operating tape therefore having its handle end disposed interiorly of the sash, of tape checking means disposed interiorly of the sash and preventing the tape from being drawn outwardly by the roller, and means acting automatically to normally urge the tape toward proper position to be retained by the check means.

5. Operating mechanism for a spring roller type awning mounted exteriorly of a sash including an operating tape therefor, having its handle end disposed interiorly of the sash, of tape checking means disposed interiorly of the sash and preventing the tape from being drawn outwardly by the roller, means acting automatically to normally urge the tape toward proper position to be retained by the check means, and means whereby a manual pull on the inner end of the tape overcomes said urging means and disengages the tape from the check means.

6. Tape guiding and controlling mechanism for an awning of the type which includes a spring roller and an operating tape, said mechanism including fixtures adapted for disposition at opposite sides of a window sash, means associated with both fixtures for guiding the tape and means associated with one fixture for normally preventing spring urged movement of the tape.

7. Tape guiding and controlling mechanism for an awning of the type which in-

cludes a spring roller and an operating tape, said mechanism including fixtures adapted for disposition at opposite sides of a window sash, means associated with both fixtures for guiding the tape, means associated with one fixture for normally preventing spring urged movement of the tape and means whereby pull on the free end of the tape renders said means inoperative.

8. Tape guiding and controlling mechanism for an awning of the type which includes a spring roller and an operating tape, said mechanism including fixtures adapted for disposition at opposite sides of a window sash, means associated with both fixtures for guiding the tape, means associated with one fixture for normally preventing spring urged movement of the tape, said means including a tape clamping eccentric and means to normally frictionally urge the tape into engagement with the eccentric.

9. Tape guiding and controlling mechanism for an awning of the type which includes a spring roller and an operating tape, said mechanism including fixtures adapted for disposition at opposite sides of a window sash, means associated with both fixtures for guiding the tape, means associated with one fixture for normally preventing spring urged movement of the tape, said means including a tape clamping eccentric, and a gravity operated member tending to hold the tape against the eccentric.

10. Tape guiding mechanism for an awning of the type which includes a spring roller and an operating tape, said mechanism including fixtures for disposition respectively at the interior and exterior of the sash, each fixture including a body, and a tape guide member vertically adjustable relatively to the body.

11. Tape guiding mechanism for an awning of the type which includes a spring roller and an operating tape, said mechanism including fixtures for disposition respectively at the interior and exterior of the sash, each fixture including a body and a tape guide member, said tape guide members each including a channel piece, tape guiding rollers mounted thereon, and the bodies having vertical slots therein along which the channel pieces are adjustable.

12. As a new article of manufacture, a fixture of the class described including a bracket, an eccentric pivoted in the bracket and a gravity operated member pendent from the bracket below the eccentric.

13. As a new article of manufacture, a fixture of the class described including a bracket, an eccentric pivoted in the bracket and a gravity operated member pendent from the bracket below the eccentric, said gravity operated member comprising a tape guiding bail operative to normally hold a

tape guided thereby in frictional engagement with the eccentric.

14. As a new article of manufacture, a fixture of the class described including an attaching portion and a flanged plate section pendent therefrom, an eccentric pivotally hung between the flanges and adapted to clamp a tape against the plate as the tape is drawn in one direction between the plate and eccentric in a manner to frictionally engage the eccentric and swing it on its pivot, and a gravity member hung from the flanges below the eccentric acting to hold the tape against the eccentric.

15. As a new article of manufacture, a fixture of the class described including an attaching portion and a flanged plate section pendent therefrom, an eccentric pivotally hung between the flanges and adapted to clamp a tape against the plate as the tape is drawn in one direction between the plate and eccentric in a manner to frictionally engage the eccentric and swing it on its pivot, and a gravity operated member hung from the flanges below the eccentric and acting to hold the tape against the eccentric, said member comprising a tape guiding bail.

16. As a new article of manufacture, an awning fixture adapted to be secured at the inside of a window and guide the inner handle end of an awning operating tape, said fixture including a channelled bracket portion, a tape clamping member movably mounted in said portion and shiftable to tape clamping position by the frictional engagement of the tape therewith as the tape is drawn in one direction through the bracket and means to normally urge the tape into frictional engagement with the clamping member.

17. Tape guiding mechanism for an awning of the type which includes a spring roller and an operating tape, said mechanism including fixtures for disposition respectively at the interior and exterior of the sash, each fixture including a body and a tape guide member vertically adjustable relatively to the body, said tape guide members each including a channel piece and tape guiding rollers mounted thereon.

18. Operating mechanism for a spring roller type awning mounted exteriorly of a sash, including an operating tape having its handle end disposed at the interior of the sash, and a tape gripping eccentric disposed interiorly of the sash normally preventing the spring roller actuated movement of the operating tape.

19. Operating mechanism for a spring roller type awning mounted exteriorly of a sash, including an operating tape having its handle end disposed at the interior of the sash, of means disposed interiorly of the sash, normally preventing the spring roller actuated movement of the operating tape,

said means including a tape gripping eccentric and means whereby the eccentric is rendered inoperative by manual movement of the handle end of the tape in a predetermined direction.

20. As a new article of manufacture, an awning fixture adapted to be secured at the inside of a window to guide the inner handle end of an awning operating tape, a tape clamping member movably mounted in said fixture and shiftable to tape clamping position by the frictional engagement of the tape therewith as the tape is drawn in one direction through the fixture, means to normally urge the tape into frictional engagement with the clamping member, said latter means being arranged for displacement to inoperative position by the tape as the handle end of the tape is manually drawn to a predetermined position whereby the manually guided tape may run freely past the clamping member without actuating the latter.

21. Operating mechanism for a spring roller type awning of the character which is adapted to be mounted exteriorly of a sash, of an operating tape having its handle end disposed at the interior of the sash, and a tape gripping eccentric disposed interiorly of the sash normally preventing the spring roller actuated movement of the operating tape, said eccentric including a tape engaging spur portion to render more positive the coaction of tape and eccentric.

Signed at New York in the county of New York and State of New York this 23rd day of May A. D. 1928.
